UNITED STATES PATENT OFFICE

ANDREW HAUGE, OF MICHIGAN CITY, INDIANA, ASSIGNOR TO SULLIVAN MACHINERY COMPANY, A CORPORATION OF MASSACHUSETTS

LOADING MACHINE

Application filed April 24, 1930. Serial No. 447,066.

This invention relates to material gathering mechanisms and more particularly to devices for loosening and gathering material to be handled by a loading machine.

One object of the invention is to provide an improved loading mechanism for gathering loose material and delivering it to a mine car or the like. Another object of the invention is to provide improved gathering mechanism for a loading machine. A further object of the invention is to provide an improved gathering mechanism which may operate in one relative positioning of its parts to loosen material to be gathered, and in another relative positioning of its parts to move the material to be gathered, towards and onto a conveyor. A still further object of the invention is to provide gathering mechanism which is so constructed and arranged that in the performance of either of the stated functions its actuating and controlling mechanisms shall interfere to a minimum degree with the carrying on of the operations. Other and more specific objects of the invention will become apparent in the course of the following description and will be more particularly pointed out in the claims.

In the accompanying drawings, in which one illustrative embodiment of the invention is shown,

Fig. 1 is a fragmentary side elevation of a loading machine provided with the illustrative form of the improved gathering mechanism.

Fig. 2 is a plan view of the front end of the same mechanism.

Fig. 3 is a vertical transverse section on line 3—3 of Fig. 1.

Fig. 4 is a detail view, partially in plan and partially in section, of one side of the gathering mechanism.

Fig. 5 is a view similar to Fig. 1, showing the parts in different positions.

Fig. 6 is a detail sectional view through the gathering and digging member.

As the particular type of loading machine with which the improved gathering mechanism cooperates is not of primary importance, the details of the loading machine as a whole are not disclosed herein. It will

be noted that by way of illustration a portion of a loading machine is shown, generally indicated at 1, and that it includes track-laying tread devices 2. A motor 3, which may drive the treads by mechanism not shown, carries at its forward end a pinion 4 for driving certain gearing subsequently to be described.

The loading machine may comprise a plurality of conveyors; and there is disclosed at 5 a gathering conveyor which may be driven by sprockets 6. Sprockets 6 are actuated as will be later described by the gearing driven from pinion 4. The flights of the gathering conveyor 5 move over a plate 7, and carry the material rearwardly and deliver it at the rear end of the gathering conveyor. Plate 7 forms part of a frame pivoted about an axis extending transversely of the machine, and with its associated parts this plate may be said to constitute, in certain aspects, a shovel member. The front of the shovel member is formed as a nose piece 9 and with this nose piece the gathering mechanism 10 cooperates.

The nose piece 9 may be forced beneath loose material, the latter passing up over the nose piece 9 and onto the conveyor 5, to be carried rearwardly and upwardly. If the loading machine comprises a second conveyor, as in a preferred form, it may, this will be arranged to receive material from the rear end of conveyor 5, and may be pivotally mounted to swing horizontally, and have provision for tilting about a horizontal axis to vary the height of the delivery end thereof.

Referring to Fig. 2, it will be noted that the gathering mechanism is carried by side arms 11 and 12, pivotally supported as at 13 and 14 on the front end of the loading machine.

The motor pinion 4 drives a bevel gear 15 keyed to a transversely extending shaft 16. This shaft is loosely surrounded by a sleeve 17 which may be connected in driven relation with the gear 15 by a friction clutch 19, normally loaded by a spring 20 and releasable by manually operable controlling mechanism 21. Sleeve 17 carries at its end remote from

the gear 15 a pinion 22, which meshes with a large spur gear 23. The latter is keyed to a transversely extending sleeve 24. The sprockets 6 are keyed to this sleeve at spaced 5 points and, as indicated above, drive the conveyor 5 through side chains 25.

A shaft 27 extends through the sleeve 24 and carries at its outer ends sprockets 28, 28. Shaft 27 may be connected for rotation either 10 in the same direction as and with sleeve 24, or in an opposite direction. A clutch member 29 is slidably, but non-rotatably secured to shaft 27 and is connectible with a pinion 30 on sleeve 24, or with a gear 31 rotating 15 oppositely to pinion 30, and driven from the latter by gear elements, 32, 33, 34. The sprockets 28 drive the gathering mechanism, as hereinafter described.

A clutch 36, having suitable control means 20 37, is provided to connect the shaft 16 to a sleeve 38. A pinion 39 on sleeve 38 meshes with a gear 40 coaxial with the shaft 27 and arranged to rotate a sprocket 41 which is connected by a chain 42 with a transverse 25 shaft 43 journaled in forwardly extending portions 44 of the body of the loading machine. This shaft carries pinions 45 which engage arcuate racks 46 secured to the arms 11 and 12 and thereby enables raising and 30 lowering of the outer ends of these arms and of the gathering mechanism carried by them. An operator controlled locking device 47 permits, by engagement with the teeth of gear 40, the holding of the arms in any desired 35 adjusted position.

As indicated in Fig. 4, the arms 11 and 12 are hollow. They are connected together for simultaneous movement by a transverse brace member 50. As the construction of the 40 arms is the same, the arm 12 only will be described in detail. At its front end is rotatably mounted a transversely extending shaft 51 carrying at the outside of the arm a crank plate 52. This plate carries a crank pin 53. The shaft 51 within the arm carries a 45 sprocket 54 which is connected by a chain 55 with a sprocket 56 rotatably supported on a shaft 57 nearer the pivot of the arm. A sprocket 57^a is secured to sprocket 56 and is actuated by the chain 57^b, which the sprocket 28 on the shaft 27 drives.

Each of the crank pins 53 carries and 50 imparts movement to a support member 58. Members 58 at their front ends support a transversely extending shaft 59, to which is suitably secured, as by welding, a built-up blade member 60 provided with replaceable teeth 61. The shaft 59 is journaled in bearings 62 and at one end, that adjacent the 55 arm 12, it carries a sprocket 63 which controls in part, with associated parts, to be described, the nature of the orbital movement of the blade 60 and teeth 61 when the crank pin 53 moves the support members 58.

60 The support members 58 are slotted at 64

to form parallel guide surfaces which cooperate with a block 65 pivotally mounted upon an extension of the shaft member 57. It will be apparent that as the crank pins 53 rotate, the supports 58 will move longitudinally and 70 that their rearward ends will be slidably guided by the guide members 65. Accordingly, the blade member 60 will be moved in a closed orbit.

To modify the orbit of the blade member 75 or digging device and make it appropriate, respectively, for breaking down standing coal and for moving the coal onto the shovel, mechanism is provided cooperating with the sprocket 63 to impart to the shaft 59 an oscillating movement as well as an orbital movement. Pivotally connected coaxially with the shaft 57 is a swinging arm 70 having a latch mechanism 71 at its rear end. This latch mechanism is adapted to secure the arm 70 in different angular relations to the arm 12 and a segment device 72 with suitable notches 73 with which the latch 71 may cooperate is secured to the arm 12. Pivotally connected adjacent the rearward end of the 80 arm 70 is a link member 74 which is at its other end connected as at 75 to a lever 76 which is secured to a shaft 77 journaled adjacent the rear end of the support member 58 which is mounted upon the arm 12. The 85 shaft 77 has keyed or otherwise non-rotatably secured thereto a sprocket 78, and this sprocket is connected with the sprocket 63 with a chain device made up of a plurality of 90 roller chain sections 80 and 81 respectively 100 cooperating with the sprocket 63 and 78, and turn-buckle devices 82 and 83 which connect the flexible portions of the chain. The sprockets 63 and 78 provide moment arms. It will be evident, referring to Fig. 5, that as 105 the arm 70 is swung from the full line position (the upper position) to the dotted line position (lower position) the arm 76 will be swung from a position in the fourth quadrant clockwise to a position in the first quadrant and accordingly the sprocket 78 will move, through the flexible connection 80, 81, 82, 83, the sprocket 63 in a clockwise direction and so cause the blade 60 and digging 110 fingers 61 to project sharply forwardly instead of downwardly.

From what has been stated, the mode of 115 operation will be readily understood. Assuming that it is desired to gather material onto the shovel, the sprockets 28 will be rotated in a counterclockwise direction viewed 120 from the left side of the machine, and accordingly the crank discs 52 will rotate in a counterclockwise direction and cause the supporting members 58 to move upwardly, forwardly, downwardly, rearwardly, and again upwardly at their outer ends and accordingly the digging elements 60, 61 will traverse 125 in a counterclockwise direction an orbit in which they will enter, and then move toward 130

the right, in Figs. 1 and 5, the material which is to be moved onto the shovel. Now it will be observed that since, during this operation of parts, the arms 70 are in the upper or full line position of Fig. 5, the blade 60 and tooth elements 61 will, in their lowest position, be substantially perpendicular to the bottom, and since the pinion 78 will receive an oscillating movement as the support members 58 move forward, down, etc., through their orbits, it will be clear that the digging elements will pivot rearwardly during the retractive movement of the supports while tending to pivot forwardly during the forward movements of the supports and thereby provide a very desirable hoeing action.

Now, if the arm 70 is moved to the dotted line position, this will cause the sprocket 78 to be moved a very substantial distance clockwise and then, with a reversal of the direction of rotation of the crank disc 52 and crank pin 53 produced by movement of the clutch member 29 into engagement with the gear element 31, the digger devices will be caused to traverse their orbit in such a manner that there will be a tendency to dig into a standing face and shovel the material over the top of the digger teeth 61 and blade 60 and downward onto the shovel.

From the foregoing description it will be evident that I have provided an improved mechanism for controlling the orbital movement of a digger device in which there is a complete elimination of all connections with the digger element except adjacent the extremity of the shaft which supports this element. Accordingly there are no links or the like to interfere with either the digging or the breaking-down operations and the entire width of the digging mechanism is unobstructed. By providing points 90 as indicated upon the ends of the arms 11 and 12 it is possible to secure a ramming action in addition to the digging action which has been described.

While there is in this application specifically described one form which this invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. A loading machine comprising, in combination, a frame, elongated supporting members, continuously rotating means for actuating said supporting members, means for guiding said supporting members by said frame whereby said members have both vertical and horizontal components of movement, material engaging means pivotally supported upon said members at the outer ends of the latter, and means for controlling

the angular position of said engaging means relative to said supporting members including a pair of oscillatable elements providing moment arms one of which is directly connected to said engaging means, means for operatively connecting said elements together, and means supported by said frame and connected to the second one of said elements for controlling the position thereof.

2. A loading machine comprising, in combination, a frame, elongated supporting members slidably guided on said frame, actuating means for said supporting members including a pin movable about an offset axis, material engaging means carried by and pivotable with respect to the outer end of the supporting members, and means for controlling said engaging means to determine the angular relation thereof to said supporting members including a pair of elements providing moment arms and both of which are carried by and movable with one of said supporting members, one of said elements being directly connected to said engaging means, linkages operatively connected to the other of said elements and to said frame, and means operatively connecting said elements together whereby upon movement of said elongated supporting members the angular motion imparted to said second element by said linkages will be transmitted substantially entirely to the engaging means through said element which is connected thereto.

3. A loading machine comprising, in combination, a frame, elongated supporting members having a guiding slot therein, means carried by said frame and projecting into said slot for supporting and guiding said supporting members, actuating means for said supporting members normally constantly rotatable in one direction and having a pivotal connection with said supporting members at points in the latter spaced from the guiding slots, a material engaging element pivotally supported at the outer end of said supporting members, a sprocket connected to said element, a second sprocket supported by said supporting members at a distance from said other sprocket, flexible means operatively connecting said sprockets, linkage mechanism connected to said second sprocket and to a relatively fixed point on said frame whereby control of said material engaging element by said linkage and sprocket mechanism is effected upon operation of said actuating means.

4. A loading machine comprising, in combination, a frame, elongated supporting members having a guiding slot therein, means carried by said frame and projecting into said slot for supporting and guiding said supporting members, actuating means for said supporting members normally constantly rotatable in one direction and having

pivotal connections with said supporting members at points offset from the axis of rotation of said actuating means, a material engaging element pivotally supported at the 5 outer end of said supporting members, a sprocket connected to said element, a second sprocket supported by said supporting member at a distance from said other sprocket, a flexible means operatively connecting said 10 sprockets, linkage mechanism operatively connected to said second sprocket and to a relatively fixed point on said frame whereby control of said engaging element by said linkage and sprocket mechanism is effected 15 upon operation of said actuating means, and means for shifting the location of the fixed point of said linkage mechanism relative to said frame.

5. A loading machine comprising, in combination, a material engaging blade, elongated supporting members therefor carried by said frame, actuating means for said supporting members to effect movement of said blade about a closed orbital path, and means 20 for controlling the inclination of said blade during its movement around said path including a sprocket directly connected to said 25

blade adjacent one of said supporting members, a second sprocket carried by said latter supporting member, an endless flexible element connecting said sprockets, and linkages connected to said second sprocket and to a 70 fixed point on said frame.

6. A loading machine comprising, in combination, a material engaging blade, elongated supporting members therefor carried by said frame, actuating means for said supporting members adapted to effect movement of said blade about a closed orbital path, means for controlling the inclination of said blade during its movement around said path including a sprocket directly connected to 75 said blade adjacent one of said elongated supporting members, a second sprocket carried by said latter supporting member, an endless flexible element connecting said 80 sprockets, linkages connected to said second sprocket and to a fixed point on said frame, and means for adjusting said fixed point including a lever adapted to have a plurality of fixed positions relative to said frame.

In testimony whereof I affix my signature. 90

ANDREW HAUGE.
